SLICING MACHINE

Harold L. Walker, Brooklyn, N. Y., assignor to
The Jacobs Bros. Co. Inc., a Corporation of
New York

Application October 22, 1930. Serial No. 490,340

2 Claims. (Cl. 146—146)

This invention relates to a functionally and structurally improved cutting machine capable of use in numerous different associations and of particular value when employed in connection 5 with the vending of commodities such as cheese and other products of similar consistency.

It is an object of the invention to furnish an apparatus of this nature in which the thickness of the slice to be dispensed or vended may be 10 varied according to the desires of the person using the machine, such variation being achieved with practically no effort on the part of the operator.

A further object of the invention is that of constructing a slicing machine in which the parts will not clog and in which each slice will be of uniform thickness.

Another object is that of providing an apparatus of this character embodying relatively few 20 parts each individually simple and rugged in construction and capable of ready assemblage to furnish a cutting machine operating over long periods of time with freedom from mechanical difficulties even when employed by unskilled operators.

With these and further objects in mind, reference is had to the attached sheets of drawings, illustrating practical embodiments of the invention, and in which:

30 Fig. 1 is an end view of a slicing machine;

Fig. 2 shows the opposite end of the machine and with the parts in a position different from that illustrated in Fig. 1;

Fig. 3 is a plan view of a slicer;

35 Fig. 4 is a transverse sectional view taken along the lines 4—4 and in the direction of the arrows indicated in Fig. 2;

Fig. 5 shows a slightly different form of mechanical arrangement from that shown in the 40 preceding views;

Fig. 6 shows a stop plate also of slightly different type from that shown in such views;

Fig. 7 is a transverse sectional view taken 45 along the lines 7—7 and in the direction of the arrows of Fig. 6;

Fig. 8 is a fragmentary plan view of an adjusting mechanism which may be employed and with certain of the parts broken away to disclose underlying construction;

50 Fig. 9 is a partly fragmentary sectional view showing a slicer embodying such adjustment;

Fig. 10 is a partly fragmentary plan view of a unit which may form a part of the adjusting mechanism particularly as shown in Figs. 8 55 and 9; and

Fig. 11 is a sectional side view of the unit as shown in Fig. 10.

In these views, the numeral 15 indicates the supports for a deck or platform 16 which as shown is preferably inclined to the horizontal 60 and may have longitudinally extending corrugations or grooves 17 which serve adequately to support the article to be sliced and to retain the same against accidental displacement. This article, according to its size, extends over a greater or lesser portion of the base or deck, but in any event, bears against the lower end of the same at which point it also rests against the end wall 18 which is preferably extended at right angles to the plane of the deck. 70

Mounted upon a shaft 19 extending below the deck is a knife support 20 which may have a U or hook shaped inner end and preferably supports at its outer end a handle 21 by means of which it may conveniently be manipulated. 75 Moreover, this support preferably carries a guard 22 extending beyond the cutting edge of a blade 23, it being obvious that by this expedient together with constructions hereinafter described the fingers of the operator will be protected to a maximum extent. Moreover, due to the hook shaped inner end 20 of the knife holder or carrying member, it will be obvious that as the blade swings downwardly in proximity to the delivery edge of the deck that a wiping stroke will 80 result instead of a straight crushing action. Movement of the holder and knife beyond predetermined points may be prevented in any desired manner by for example extending the holder 20 as has been indicated at 24 and to provide in 85 cooperation with a pin 25 extending from below the deck of the machine a construction acting as a stop. 90

In a machine of this character, it is usually necessary to provide a construction acting to 95 limit the distance to which the article to be sliced may be projected, and thus accordingly to limit and control the thicknesses of the slices into which the article is cut. With this in mind, the present machine includes a stop or gauge plate 26 which is mounted upon a shaft 27, this shaft being coupled to the shaft 19 by for example a link or pitman 28 which has its opposite ends mounted between crank portions 29 and 30 100 extending from these shafts. Due to the fact that a differential rate of movement is desired between the knife and the stop plate, these crank portions may be offset as has been shown particularly in Figs. 1 and 3. Accordingly, the holder and knife carried thereby may be swung down- 105

wardly from the position shown in the first figure and the stop plate will not have a movement as great as that of the knife and holder. Accordingly, an article resting upon the deck and bearing against the stop plate will remain even under constant pressure towards the stop plate in proper position until the edge of the knife engages it and in fact the support and restraining influence exerted by the stop plate will not cease until the cutting edge has cut substantially through the entire body of the article being sliced. To again prevent accidental displacement of the article although preventing any binding tendency of the parts, the face of the stop plate 15 may be grooved arcuately as has been indicated at 31, these arcs being segments of concentric circles having as their center the shaft 27.

Now with a view to providing a suitable mechanism whereby the distance between the edge of the deck and the inner face of the stop plate may be properly varied, reference is had to Fig. 4. In this view, the numeral 32 indicates a knob which as in Fig. 3 may have graduations upon its face and which graduations register with an indicator or pointer formed by the upper edge of a rib or projection 33. This knob is rotatably mounted upon the end of the shaft 27, and a spring 35 normally maintains a cam edge or skirt portion 36 forming a part of this knob in contact with the projection 33. This cam edge as shown preferably presents rest portions corresponding in number and in depth thereof to the graduations presented by the knob. In view of the fact that the spring 35 normally serves to impel the shaft 30 27 outwardly, a turning of the knob will serve to space the stop 26 to a greater or lesser extent from the plane of the outer or delivery edge of the deck. Accordingly, with each elevation of the holder and knife and under continued pressure upon the article being sliced, this article will move to a point where it contacts with the stop plate and according to the position of the latter—as controlled by the knob 32—the slices will be of any desired thickness.

In certain instances, it may be desired to prevent any possibility of adhesion between the slice and stop plate. With this in mind, the stop plate may be given a movement away from contact with the outer face of the article being sliced 50 as the latter is severed. A convenient construction according to the present invention to accomplish this result is disclosed in Fig. 5 in which the shaft 27 is hollow as has been indicated at 37, and there rides within this shaft or tube a second shaft 38 to the outer end of which there is rotatably attached the knob (not shown). Connection between the tube 37 and the shaft 38 is afforded by a pin and slot construction 39, the slot being inclined in the direction of the delivery edge of the deck. A guide structure 40 prevents rotation of the shaft 38. Accordingly as the knob 32 is turned, this shaft is adjusted longitudinally in the manner afore described to vary the thickness of the slice, this being accomplished due to the fact that any thrust upon the shaft will be transmitted by the pin and slot connection. However, as afore brought out, the stop or gauge plate swings and this is accomplished by rotating the tube 37. Accordingly, with the parts properly set, proper thickness of slice is initiated and the cutting edge of the blade bears against the article to sever a desired portion of the same. As this movement of the parts occurs, the tube 37 rotates with respect to the shaft 38 thereby causing the pin to traverse the slot causing the tube to

be projected slightly under continued movement of the parts. This results in the stop plate moving outwardly through a slight distance and particularly through the final severing stages of the slice. Consequently, the stop plate separates from contact with the outer face of the slice and free delivery of the latter is effected.

In certain instances, it may not be desired to employ this construction. Within certain limitations, the same results may be achieved by the use of a stop plate 41 having a rearwardly inclined face 42. Under normal operation of the parts, the article bears against the inner face of the plate. A downward swinging of the holder and knife causes contact to be effected between the cutting edge of the latter and the article and thereupon under continued downward swinging of the plate the face of the latter—due to its tapered construction—clears the slice being cut.

In the form of construction shown in Figs. 8 and 9, adjustment of the shaft 43 which carries the stop plate may be achieved by the use of a lever 44 having its inner end pivoted and its outer end carrying the knob 45 registering with graduations 46 arranged for example in the face of an extension forming a part of the machine. Obviously, as the lever is shifted, the shaft will be shifted to vary the thicknesses of the slices. The additional advantage arises by this construction that if the zero or minimum slicing thickness occurs with the lever set at substantially right angles to the shaft 43, this lever will have its slot 47—within which the pin 48 of the shaft 43 rides—extend angularly as the parts are adjusted to give increased slicing thickness. Consequently, the shaft 43 in rotating will move slightly outwardly again giving the advantage of clearance between the end slice of the article and the inner face of the stop plate.

Where such movement is not desired, the results 115 may be achieved by substituting for the pin and slot connection 47—48, a pin 49 carried by the lever 44 and riding within a groove 50 formed in the shaft 43. Obviously, under this construction, the desired adjustment will be accomplished without, however, there being any outward movement of the shaft except when adjustment is made to vary the thickness of the slice.

In each instance, it will be appreciated that the knife serves as a stop for the main body of the article and during the slicing of the latter. After severance of the slice, the article does not move forward until the knife clears the same whereupon under continued pressure the article shifts and contacts with the stop plate. If desired, the paper holder or shelf 51 may be associated with any convenient portion of the machine and the latter may have a recess accommodating an oil stone or sharpening element 52 which is retained by a spring clip 53. Also, it is preferred, according to the present invention, and as has been indicated in Fig. 4, that the cutting edge of the knife 22 may be formed by an outwardly extending face 54 which lies at an acute angle to the inner face of the blade and which face is continued in a secondary face 55 extending at an obtuse angle to the first face. By this construction, adhesion between the article being sliced and the face of the knife is prevented.

Obviously, any number of changes in construction may be resorted to without departing from the spirit of the invention as defined by the claims.

Having described my invention, what I claim

as new and desire to secure by Letters Patent, is:

1. A slicing machine including, a deck, a knife pivotally carried at one end thereof, a stop plate pivotally mounted by said deck adjacent said knife and adapted to move in a plane substantially that of the path of movement of said knife, means coupling said knife and stop plate for simultaneous movement about their respective pivots, and additional means for automatically imparting an incidental lateral movement away from said deck to said stop plate as said knife is being lowered.

2. A slicing machine including, a deck, a knife pivotally secured to one end thereof, a stop plate pivotally mounted by said deck adjacent said knife and adapted to move in a plane substantially that of the path of movement of said knife, said stop plate being formed with a sloping inner surface, means coupling said knife and stop plate for simultaneous movement about their pivots, and further means for causing an automatic lateral movement of said stop plate away from said deck as said knife is lowered.
